UNITED STATES PATENT OFFICE

165,264

GLASS BOWL OR SIMILAR ARTICLE

Charles W. Carlson, Tiffin, Ohio

Application March 9, 1951, Serial No. 14,442

Term of patent 14 years

(Cl. D36—8)

To all whom it may concern:

Be it known that I, Charles W. Carlson, a citizen of the United States, residing in Tiffin, Ohio, have invented a new, original, and ornamental Design for a Glass Bowl or Similar Article, of which the following is a specification, reference being had to the accompanying drawing, forming part thereof.

In the drawing:

Fig. 1 is an elevational view of a glass bowl, showing my new design;

Fig. 2 is a similar elevational view taken at an angle of 45° to Fig. 1;

Fig. 3 is a horizontal cross-sectional view on the line III—III of Fig. 1; and

Fig. 4 is a horizontal cross-sectional view on the line IV—IV of Fig. 1.

The dominant features of the design reside in the part drawn in full lines, as shown.

I claim:

The ornamental design for a glass bowl or similar article, as shown and described.

CHARLES W. CARLSON.
